Attorney

UNITED STATES PATENT OFFICE.

WILLIAM P. BRAUN AND ALBERT BRAUN, OF BROOKLYN, NEW YORK.

METHOD OF MAKING BRUSHES.

Application filed August 3, 1921. Serial No. 489,454.

To all whom it may concern:

Be it known that we, WILLIAM P. BRAUN and ALBERT BRAUN, citizens of the United States, residing at Brooklyn, in the county 5 of Kings and State of New York, have invented certain new and useful Improvements in Methods of Making Brushes, of which the following is a specification, reference being had therein to the accompanying 10 drawing.

This invention relates to a novel method for making brushes.

The primary object of the invention is to furnish an improved method for making 15 a brush of simple and inexpensive construction which may be readily and expeditiously manufactured from stock material.

Another object of the invention is to furnish an improved method for inserting the 20 bristles into the handle and for securely locking the bristles in position.

With the foregoing objects outlined and with other objects in view which will appear as the description proceeds, the invention 25 consists in the novel method herein-after described in detail, illustrated in the accompanying drawing and more particularly pointed out in the appended claims.

Referring to the drawing;

30 Figure 1 is a longitudinal sectional view of a complete brush manufactured in accordance with our method.

Figure 2 is a similar view showing the brush handle, bristles and fastening means 35 prior to the insertion of the bristles into the ferrule.

Figure 3 is a transverse sectional view taken on line 3—3 of Figure 2.

Figure 4 is a view similar to Figure 1, 40 showing the position of the bristles after they have been forced part way into the ferrule.

In the drawing, 1 designates a hollow or tubular brush handle provided at one end 45 with an enlarged tubular portion 2. 3 designates suitable brush material such as bristles, and 4 the means for forcing the bristles into the enlarged tubular portion and for locking the same within said tubular portion. The member 4 consists preferably of a single piece of wire which before the brush is formed is bent to provide 50 opposite legs 5 connected together by a cross head or a loop 6. The legs 5 are inserted 55 through the passage way 7 in the handle 1

until the loop 6 contacts with the head 8 of the handle. At this time the extremities of the legs 5 project beyond the outer end 9 of the tubular portion 2 and a tuft of bristles or other brush material is placed on the end 60 9 between the legs. Subsequently the loop 6 and the extremities of the legs 5, are twisted in opposite directions and this will cause the legs to be twisted within the handle, as shown at 10, and will also cause 65 the twisted portion 11 above the bristles or other brush material to force said bristles or material into the enlarged tubular portion in the manner indicated in Figure 4. The twisting is continued until the bristles 70 or other brush material occupy the position shown by Figure 1, at which time the end portions of the legs 5 are cut off at a point 12 and the ends 13 of the bristles or other brush material are trimmed to provide 75 a complete brush.

The brush formed by this method has bristles or other brush material which are securely locked in position, and it has been found in practice that these bristles or other 80 material will remain in this position until the brush is worn out.

From the foregoing, we believe that the steps of the method, and advantages of the invention may be readily understood by 85 those skilled in the art, and we are aware that various changes may be made in the method described, without departing from the spirit of the invention as expressed in the claims. 90

What we claim and desire to secure by Letters Patent is:

1. A method of manufacturing brushes consisting in providing a hollow handle having an enlarged tubular portion at one 95 end, inserting a double wire through said handle and tubular portion, placing brush material between said wires, and twisting said wires together to force the material into the enlarged tubular portion. 100

2. A method of manufacturing brushes consisting in providing a tubular member, inserting a plurality of strands of wire through said member, placing brush material between said strands, and twisting said 105 strands together to force the material into said tubular member.

3. A method of manufacturing brushes consisting in providing a tubular member, inserting a plurality of strands of wire 110

through said member, placing brush material between said strands, twisting said strands together to force the material into said tubular member, and cutting the end 5 portions of said strands after the brush material has been forced into said tubular member.

In testimony whereof we hereunto affix

our signatures in the presence of two witnesses.

WILLIAM P. BRAUN. [L. S.]
ALBERT BRAUN. [L. S.]
